(57) **CLAIM**

The ornamental design for a display screen with transitional graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image of a first embodiment of a display screen with transitional graphical user interface according to the claimed design;

FIG. 2 is a front view of a second image thereof;

FIG. 3 is a front view of a first image of a second embodiment of a display screen with transitional graphical user interface;

FIG. 4 is a front view of a second image thereof;

FIG. 5 is a front view of third image thereof;

FIG. 6 is a front view of a fourth image thereof;

FIG. 7 is a front view of a first image of a third embodiment of a display screen with transitional graphical user interface according to the claimed design;

FIG. 8 is a front view of a second image thereof;

FIG. 9 is a front view of a first image of a fourth embodiment of a display screen with transitional graphical user interface;

FIG. 10 is a front view of a second image thereof;

FIG. 11 is a front view of third image thereof; and,

FIG. 12 is a front view of a fourth image thereof.

The appearance of the transition is sequential from FIG. 1 to FIG. 2 in the first embodiment, from FIG. 3 to FIGS. 4, 5 and 6 in the second embodiment, from FIG. 7 to FIG. 8 in the third embodiment, and from FIG. 9 to FIGS. 10, 11 and 12 in the fourth embodiment. The process or period in which an image transitions to another image forms no part of the claimed design.
